ATTORNEY,

UNITED STATES PATENT OFFICE.

MARY V. BRUNK, OF KANSAS CITY, KANSAS.

DESIGN FOR A METAL SHOE-SOLE.

52,729.

Specification for Design.

Patented Dec. 10, 1918.

Application filed December 1, 1915. Serial No. 64,604. Term of patent 7 years.

To all whom it may concern:

Be it known that I, MARY V. BRUNK, a citizen of the United States, residing at Kansas City, in the county of Wyandotte and State of Kansas, have invented a new, original, and ornamental Design for Metal Shoe-Soles, of which the following is a specification, reference being had to the accompanying drawing, which shows a per-

spective view of a shoe sole illustrating my new design.

I claim:

The ornamental design for a metal shoe sole, as shown.

MARY V. BRUNK.

Witnesses:

F. G. FISCHER,
L. J. FISCHER.
